UNITED STATES PATENT OFFICE

PERCY M. FORSTER, OF BERKELEY, CALIFORNIA

DESIGN FOR A DENTAL GAS BURNER

Application filed August 18, 1930. Serial No. 36,698. Term of patent 14 years.

To all whom it may concern:

Be it known that I, Percy M. Forster, a citizen of the United States, residing at Berkeley, county of Alameda, State of California, have invented a new, original, and ornamental Design for Dental Gas Burner, of which the following is a specification, reference being had to the accompanying drawings, forming part thereof.

The figure is a perspective view of the dental gas burner illustrating my new design.

I claim:

The ornamental design for a dental gas burner substantially as shown.

PERCY M. FORSTER.
